CLAIM

The ornamental design for a syringe barrel with divided petaloid tip, as shown and described.

DESCRIPTION

FIG. 1 is a top plan view;

FIG. 2 is a top perspective view;

FIG. 3 is a bottom perspective view;

FIG. 4 is a bottom plan view;

FIG. 5 is a front elevation view, which is the same as the rear elevation view; and,

FIG. 6 is a left side elevation view, which is the same as the right side elevation view.

The broken line define the boundaries of the claimed design and depict portions of the syringe barrel with divided petaloid tip that form no part of the claimed design.

1 Claim, 2 Drawing Sheets
